UNITED STATES PATENT OFFICE.

SMITH MAXWELL, OF KNIGHTSVILLE, INDIANA, ASSIGNOR OF ONE-THIRD TO
MICHAEL HENNESSY AND ONE-THIRD TO ARTHUR MAXWELL, BOTH OF
KNIGHTSVILLE, INDIANA.

FROG SWITCH.

Application filed February 18, 1922. Serial No. 537,510.

To all whom it may concern:

Be it known that I, SMITH MAXWELL, a citizen of the United States, residing at Knightsville, in the county of Clay and 5 State of Indiana, have invented new and useful Improvements in Frog Switches, of which the following is a specification.

This invention relates to railway track constructions, and has for one of its objects, 10 the provision of a frog switch including a tongue adapted to move across one of the rails on the main track, and occupy a position upon a frog block and in alinement with one of the rails of the siding, a construction which does not weaken the said rail of the main track, which usually results when said rail is cut away to accommodate a frog switch.

Another object of the invention resides 20 in the construction of means for simultaneously operating the frog switch with the switch points, and providing a connection between the frog switch and a semaphore, whereby the latter is operated incident to 25 the movement of the frog switch.

The nature and advantages of the invention will be better understood when the following detailed description is read in connection with the accompanying drawings, 30 the invention residing in the construction, combination, and arrangement of parts as claimed.

In the drawings forming part of this application, like numerals of reference indicate 35 similar parts in the several views, and wherein:

Figure 1 is a perspective view showing the relative position of the parts when the main trackway is open.

40 Figure 2 is a transverse sectional view taken on line 2—2 of Figure 1.

Figure 3 is a view similar to Figure 1 showing the frog in its active position across the main track and in alinement 45 with the adjacent rail of the siding.

Figure 4 is a transverse sectional view taken on line 4—4 of Figure 3.

Figure 5 is a perspective view of the frog switch.

50 Referring to the drawings in detail, 10 and 11 indicate respectively the rails of the main track, while 12 and 13 represent the rails of the siding. Pivoted as at 14 are switch points 15, the latter being movable between

the rail 10 of the main track and the rail 12 of the siding.

The switch points are connected together by a bridle 16 which slides beneath the rails, and connected at one end to an operating shaft 17. The shaft is journaled in a suitable bearing 18 and is provided with a handle or operating lever 19.

Arranged between the rails of the main trackway, but in juxtaposition to the rail 11, is a frog block indicated at 21, and this 65 block is further disposed in alinement, or substantially so with the rail 13 of the siding. The upper surface of this frog block is recessed as at 22, the recess opening at one side of the block to receive the tongue of 70 the frog switch to be hereinafter described. This frog block is further cut away as at 23 so that the upper surface at one side of the block is arranged beneath the head of the rail 11 of the main trackway, it being 75 understood that the flanges of the wheels pass over this portion of the block when the train traverses the main track. Pivoted at the opposite side of the rail 11 is a frog switch 24 which is formed to provide a 80 tongue or extension 25 adapted to overlie the head of the rail 11 of the main trackway, when it is shifted to a position to form a continuity of the rail 13 of the siding. In this position of parts as illustrated 85 in Figures 3 and 4, the tongue or extension 25 is positioned within the recess 22 of the frog block. The frog switch is reduced and slightly tapered as at 27 immediately beneath the tongue 25 so that the switch can 90 be moved into proper and close association with the rail 11 of the main track when its use is desired.

The frog switch is shifted simultaneously 95 with the switch points 15, being connected with the latter through the instrumentality of the mechanism to be presently described. This mechanism includes a bridle 28 which extends beneath the rails of both the main track and siding, and connected to the joints 100 of the switch points 15.

One end of this bridle 28 is pivotally connected to the adjacent branch 29 of a bell crank lever 30 which is fulcrumed as at 31. The remaining branch 32 of this bell crank 105 lever is pivotally connected to the adjacent extremity of a connecting rod 33, the opposite end being pivotally connected to the

adjacent branch 34 of a second bell crank lever indicated at 35 and fulcrumed as at 36. It will be noted that the bell crank lever 35 is disposed reversely to the bell 5 crank lever 30. The remaining branch 37 of the bell crank lever 35 is connected by means of an arm 38 to the frog switch above referred to. The frog switch supports a bracket 39, and the adjacent end of the connecting rod is offset as at 40 and pivotally associated with the said bracket 39. Manifestly, when the operating handle or lever 19 is actuated to shift the switch points 15, 10 the frog switch is simultaneously operated, and may be moved in either direction, this 15 of course depending upon the particular direction of movement of the handle or operating lever 19.

Arranged adjacent the track structure is 20 a post or standard 41 upon which is pivoted a semaphore 42, the latter being connected by a rod 43 to the adjacent branch 44 of a bell crank lever 45. This lever is fulcrumed upon the standard 41, and has its 25 remaining branch 46 connected with the adjacent end of an arm 47, the opposite end of this arm being pivotally associated with a bracket 48 carried by the frog switch. Manifestly, when the frog switch is actuated to 30 overlie the adjacent rail of the main track, the semaphore is moved to a position against the main line traffic.

While it is believed that from the foregoing description, the nature and advantages 35 of the invention will be readily apparent, I desire to have it understood that I do not so limit myself.

What I claim is:—

1. In a railway construction, a main track, 40 a siding, switch points pivoted between the adjacent rails of the main track and siding, means connecting said switch points whereby the latter are simultaneously movable, a frog block arranged between the rails of 45 the main track but in juxtaposition to one of said rails, said block being also disposed

substantially in aline with the adjacent rail of the siding, said block being cut away at one side whereby a portion of said block lies beneath the head of the adjacent rail 50 of the main track, a frog switch pivoted at the opposite side of the last mentioned rail, a tongue projecting from said frog switch and adapted to move across and overlie the adjacent rail of the main track when in 55 active position, said frog block having a recess in its upper surface to receive said tongue, a bridle connecting the switch points, spaced oppositely disposed bell crank levers, a connecting rod between said levers, 60 said bridle being connected to one of said levers, and a connection between the other of said levers and the frog switch whereby the latter is simultaneously movable with said switch points. 65

2. In a railway construction, a main track, a siding, switch points movable between the adjacent rails of the main track and said siding, means for connecting said switch points for simultaneous movement, a frog 70 block arranged between the rails of the main track and in juxtaposition to one of said rails, said block being further disposed substantially in aline with the adjacent rail of the siding, a frog pivoted at one side of the 75 adjacent rail of the main track, a tongue projecting from said frog switch and adapted to be moved across and overlie the adjacent rail of the main track, said frog block having a recess in its upper face to receive 80 said tongue, means connecting the frog switch with said switch points for simultaneous movement with the latter, a semaphore pivotally mounted adjacent the track-way, and means connecting the semaphore 85 with the frog switch, whereby said semaphore is actuated incident to movement of said switch.

In testimony whereof I affix my signature.

SMITH MAXWELL.
